UNITED STATES PATENT OFFICE

2,602,390

VENTILATOR

Samuel H. Whissel, Tulsa, Okla.

Application November 8, 1946, Serial No. 708,665

2 Claims. (Cl. 98—88)

1

This invention relates to ventilators for windows and other openings to provide ventilation and make a house cooler and more comfortable in the summer by preventing the sun from radiating heat through the glass of the sash and at the same time automatically closing in case of a wind or rain storm, by the pressure of the wind against the slats or blinds thereof, but to return to normal open position when the wind pressure is reduced to a certain point determined by the balance of the slats or blinds.

Another object of the invention is to provide a ventilator having movable slats so balanced that they will all simultaneously move to open and closed positions, and normally to open positions but will close automatically under wind pressure when there is a wind or rain storm, so as to exclude rain from the windows and protect the latter in severe storms, while also permitting the use of screens therewith to exclude dust and insects.

Another object of the invention is to provide means for securing the slats or blinds of the ventilator in open or closed positions.

Another object of the invention is to provide a ventilator in which the slats or blinds are pivoted in a novel manner to balance the same to normally open, and which are constructed in a simple and novel manner capable of economical manufacture and assembly as well as installation, and by which anyone of the individual slats or blinds may be removed independently of the others, while acting to give a tighter seal the stronger the wind, in addition to being capable of being held in adjusted open position or closed position and protecting the contents of a room.

Other objects and advantages reside in the details of construction and operation as more fully hereinafter described and claimed, reference being had to the accompanying drawings forming part hereof, wherein like numerals refer to like parts throughout, and in which:

Figure 1 is a front elevation of a ventilator constructed in accordance with the invention as applied to a window.

Figure 2 is an enlarged vertical sectional view thereof.

Figure 3 is an enlarged fragmentary view of the lower portion of a sash showing the ventilator construction and mounting.

Figure 4 is a sectional view taken on the line 4—4 of Figure 3.

Figure 5 is a fragmentary front elevational view;

Figure 6 is a fragmentary perspective view of the upper portion of the ventilator at one side, and

Figure 7 is a fragmentary view in vertical section through a modified form of the invention, showing the slats in closed position.

Referring to the drawings in detail, in which like reference characters designate like parts throughout the several views, the numeral 10 designates a window frame having the inner stop 11 and the intermediate stop or parting strip 12 extending to the sill 13. Movable in the frame is an upper sash 14 and a lower sash 15 shown in open position in Figure 2, and all of standard construction. The upper portion of the ventilator includes a plurality of inclined slats or blinds 16 arranged within the outer stops 17 which are provided with spaced transverse grooves 18, in order to securely receive the ends of the slats and retain the slats in outwardly inclined positions and in parallel relation to each other against the frame of the upper sash 14. The slats 16 project outwardly beyond the stops 17 and vertical strips 19 are fixed on the ends thereof. This provides means for ventilating rooms as well as halls, attics and the like while excluding the radiation from the sun through the glass of the windows, thereby rendering the interior cooler and permitting the entrance of air when the opening is unobstructed by sash or the latter are open. Of course, the upper sash may be closed or partially open. In addition, a screen 20 having a frame 21, may be provided outwardly of the ventilator within the frame 10 to exclude dust and dirt as well as insects and may be provided with a transverse horizontal intermediate strip 22 or the latter may be omitted. The frame 21 and the strip 22 may seat against the outer stop 17. While the ventilator at the top, adapted for hallways, windows or openings therein, or in attic spaces, may be stationary or fixed in position as described, the same may be adapted to open and close as will now be described in connection with the ventilator which fits below the upper sash 14.

This ventilator construction includes a frame having sides formed by the lower portion of the

stops 17 on the sides of the frame 10, and an L-shaped bottom member 23 secured to the lower ends of the stop 17. The bottom member 23 is supported upon a strip or block 24 at the bottom of the frame 10 and sealed by the bottom of the screen frame 21, as shown more particularly in Figure 3 of the drawings. Vertically of the sides of the stops 17 are narrow grooves 25 across which at vertically spaced intervals, bearing supports 26 in the form of nails, brads, or other inserts are secured forming bearings for the pivots 27 of the slats or blinds 28 at the ends of the latter. These blinds may be of plastic, metal, wood or other material and the pivots are located slightly off-center to the rear or inside. The ends of the strips forming the slats or blinds are provided with attached or integral hangers 29 depending from the ends thereof at their inner portions and bent from the ends of the slats or attached thereto, a desirable construction being to form the slats and hangers of a single blank of galvanized sheet metal or the like. Extending between the members 17, above the slats 28, is a cover or roof 30 sloping outwardly and formed with a rabbeted edge or recess 31, against which the upper slat moves in a closed position to form a stop, as well as the roof serving as a canopy or cover to prevent the entrance of rain water behind the slats or blinds. It should also be noted that the pivots 27 are loosely mounted in the grooves 25 and rest on the bearing supports 26, in order to turn freely and without friction.

At their inner ends, the hangers 29, which are tapered and shaped as shown, are apertured for pivotal connection to connecting strips, wires or rods 32, the openings 33 in the hangers 29 loosely receiving the pivots 34 carried by the connecting strips 32 which are also preferably rabbeted on the inside as indicated at 35, to provide inwardly extending flanges 36 at the inside. A cushion 37 of sponge rubber, felt or the like may be provided on the top of the connecting or operating bars or strips 32 to strike the bottom of the upper sash when the slats or blinds oscillate in the wind, to avoid noise when there is a storm, either wind or rain.

Since all of the slats or blinds are connected by the strips, rods or bars 32, they will move together, and they are so balanced on their pivots that they are normally held open by gravity by the strips 32, but under the pressure of the wind in a wind or rain storm, said slats will be forced to closed position, to protect the interior sash of a building as well as contents, drapes and the like by sealing the window opening in a manner shown in Figure 2 of the drawings, this action being automatic due to the pressure of the wind. However, when the pressure is reduced to a certain point, the slats or blinds will then automatically open to the balanced position in which they are pivoted. However, means is provided to hold the blinds in adjusted open or closed position, such as by chains of the ball type indicated at 38 attached at suitable points on the strips 32 to engage beneath the hooks 39 fastened to the inner edges of the stop or parting strips 12. In this way, the window opening is closed at the bottom or at such other points as the ventilator is provided while permitting a certain amount of ventilation from outside air. Also, it will be apparent that while the house provided with such ventilators will be cooler and more comfortable, a good degree of privacy will also be provided since it will be difficult to see inside of a room from the outside, while permitting the entrance of light

when the blinds or slats are in open position, while also permitting view of the outside from the interior, and when the slats or blinds of the ventilator are closed, permitting absolute privacy by preventing a view of the inside from the outside of the building, while still permitting some ventilation. Of course, it is to be understood that the device may be employed with or without screens and that the entire window opening may be equipped with the ventilator having the movable slats or blinds balanced and adapted to open and close as described, without departing from the spirit of the invention. Also, since the screen frame 21 may be hinged at the top as indicated at 40 or mounted on other similar detachable hangers in the manner of screens or storm sash, the screen frame 21 may be fastened at the bottom in any suitable way, such as by means of hooks 41 engaging eyes 42, to retain the screen frames in position and prevent access to the ventilator from the exterior.

In Figure 7, the slats or blinds 28' are shown made of sheet material, such as metal, plastic or the like with ends bent to form integral hangers 29' shaped as described in connection with slats 28 and having holes 27' to receive pivots 27 and openings 33' the same as openings 33 to receive pivots 34 as previously described. Also, the inner or top longitudinal edges of slats 28' are turned up preferably at a 90 degree angle as at 34' and the outer or bottom longitudinal edges are turned down preferably at a 45 degree angle as at 35' to serve another important purpose or function on this automatic ventilator which it does not serve on an ordinary one, namely, as a stabilizer for the slats. It forms enough air resistance to prevent too rapid action of the slats, so that as the slats come near the closing point they form air traps between them which force the air back against the turned edges or flanges of the slats above or adjacent thereto, thereby forming air cushions or brakes to make the slats close gently and quietly without a bang or noise such as by sudden closing. This is very important to the operation of the ventilator as it is controlled and operated by wind pressure and operates quietly and automatically.

While in the foregoing there has been shown and described the preferred embodiment of this invention it is to be understood that minor changes in the details of construction, combination and arrangement of parts may be resorted to without departing from the spirit and scope of the invention as claimed.

I claim:

1. In a louver construction including a frame having parallel spaced sides formed with vertical grooves in their inner faces, support members mounted transversely across the grooves and vertically spaced on the sides, slats having projections offset inwardly and projecting from the ends of the slats, said projections being disposed in the grooves and resting on the support members to pivotally mount the slats.

2. A ventilator comprising a frame adapted to be mounted in an opening and having parallel sides formed with vertical grooves, transverse supports mounted in the grooves, slats having projecting studs extending from their opposed ends, said studs being disposed in the grooves and freely resting on the supports, whereby the slats can move into overlapping relation in closed position or in parallel inclined position when open, hangers extending inwardly and downwardly from the slats and bent from the ends

thereof, and connecting bars between said hangers and vertically movable in the frame sides for effecting simultaneous movement of the slats.

SAMUEL H. WHISSEL.
